(57) **CLAIM**

The ornamental design for packaging for flowers, as shown and described.

DESCRIPTION

FIG. 1 is a top, side and end perspective view of packaging for flowers, showing my new design;

FIG. 2 is a side elevational view thereof, the appearance of the side opposite that shown in FIG. 2 being identical thereto;

FIG. 3 is an end elevational view thereof, the appearance of the end opposite that shown in FIG. 3 being identical thereto;

FIG. 4 is a top plan view thereof; and,

FIG. 5 is a bottom plan view thereof.
